(57) **CLAIM**

I claim the ornamental design for a shade apparatus for broiler poultry house, as shown and described.

DESCRIPTION

FIG. 1 is a perspective view of a shade apparatus for a broiler poultry house according to the invention;

FIG. 2 is another perspective view thereof;

FIG. 3 is a front elevation view thereof;

FIG. 4 is a top plan view thereof;

FIG. 5 is a bottom plan view thereof;

FIG. 6 is a rear elevation thereof;

FIG. 7 is a left side view thereof; and,

FIG. 8 is a right side view thereof.

1 Claim, 4 Drawing Sheets
